US0D1079211S

(12) **United States Design Patent** (10) Patent No.: **US D1,079,211 S**
(45) Date of Patent: ** Jun. 17, 2025

(54) **SHOE**

(71) Applicant: **AZZEDINE ALAIA SAS**, Paris (FR)

(72) Inventor: **Tiziana Capraro**, Paris (FR)

(**) Term: **15 Years**

(21) Appl. No.: **35/522,616**

(22) Filed: **Jul. 22, 2024**

(80) **Hague Agreement Data**

Int. Filing Date: **Jul. 22, 2024**

Int. Reg. No.: **DM/240721**

Int. Reg. Date: **Jul. 22, 2024**

Int. Reg. Pub. Date: **Oct. 11, 2024**

(30) **Foreign Application Priority Data**

Jan. 23, 2024 (EM) 015048315-0001

(51) **LOC (15) Cl.** **02-04**

(52) **U.S. Cl.**

USPC **D2/930**; D2/929; D2/925
